APPARATUS FOR PELLETING CARBON BLACK

Samuel C. Carney, Bartlesville, Okla., assignor to
Phillips Petroleum Company, a corporation of
Delaware

Application May 16, 1939, Serial No. 274,003

6 Claims. (CL 259—3)

My invention relates to apparatus for use in pelleting carbon black and more particularly to apparatus for transforming the dusty light carbon as produced into pellets without any preliminary densification of the black or any foreign substance being added to the black to effect agglomeration.

An important object of the invention is to provide an apparatus for agglomerating dusty light carbon black particles in a closed cycle in accordance with the process set forth in applicant's copending application Serial No. 259,065 filed February 28, 1939.

A further object of the invention is to provide an apparatus to which the dusty light carbon black particles will be less likely to adhere during the process of agglomeration.

A still further object of the invention is to provide an apparatus which is less expensive to manufacture than present apparatus used in the dry process for agglomerating carbon black, the power requirements for operation of the apparatus are materially less and the apparatus operates with a greater degree of certainty with less chance for failure of the process.

Other objects and advantages of the invention will be apparent during the course of the following description.

In the accompanying drawings, forming a part of this specification, and in which like numerals are employed to designate like parts throughout the same,

Figure 1 is a side elevational view of one type of apparatus of the present invention,

Figure 2 is a sectional view taken on the line 2—2 of Figure 1,

Figure 3 is a sectional view taken on the line 3—3 of Figure 1,

Figure 4 is a side elevational view of another type of apparatus of the present invention,

Figure 5 is a sectional view taken on the line 4—4 of Figure 4, and

Figure 6 is a sectional view taken on the line 5—5 of Figure 4.

In the drawings, wherein for the purpose of illustration, is shown a preferred embodiment of my invention, the numeral 1 designates a drum having spirally wrapped thereon a rubber hose or conduit 2. The hose or conduit has a smooth inner surface and is suitably reinforced by fabric and wire so as to retain a circular cross-section. For a practical sized unit, pelleting 10 pounds of carbon black per minute, the drum will be about 8 feet in diameter, 5 feet long and wrapped with a hose or conduit 8 inches in diameter

5 with 4 such drums used in a cycle. The cylindrical part of the drum may be a light, skeleton construction for its sole purpose is to maintain the hose or conduit in position so as to make of the hose or conduit an Archimedes spiral.

In pouring granules down a stationary tube or incline at a fixed rate, say 1,000 pounds per minute, the cross-section determines the velocity. This is not true when movement is in a moving annulus or tube. Here relative velocity is that of the moving wall of the apparatus and the moving container may therefore, have any desired cross-section to give any desired residence time to a closed cycle process, and the effective velocity of movement is the peripheral speed of the apparatus.

There are clear advantages to the use of rubber tubes as against metal apparatus because of the ease of construction, freedom from carbon sticking to the walls and the better surface of rubber for inducing rotary motion. There are also distinct advantages to a closed cycle with an adjustable cycle ratio against the feed stream.

The drum 1 has a shaft 3 going through the center thereof mounted in suitable bearings in the head portions 4 and 5 of the drum. At each end of the drum, supporting members 6 and 7 attach to the shaft 3 and support the drum in a rotatable position. Suitable motor means may 20 be attached to the shaft 3 to rotate the drum 1. This motor means forms no part of the invention and may be any known motor means, preferably some electric motor.

The numeral 8 represents the inlet line through 35 which the cyclic granules, in amount 50 to 100 times the total feed, flow continuously from one rotating unit to another and back to the first in a closed cycle and 9 is a feed line in which raw feed is added to the cycle. Seed is also added 40 through line 9 but seed may all be added at one point, while it is desirable that feed be added at the inlet of each rotating unit. Line 8 enters rotating inlet chamber 10 below the center and at one side so as to clear the bearing pedestal. Line 8 enters the rotating chamber 10 through the stationary cover plate 11 which is held loosely by springs 12 against the rotating nozzle flange 13.

Referring now to Figure 3, rotation of the 50 chamber 10 is indicated by the arrow A. The circumference of the chamber 10 is cut at 14 and nozzle 15 is set into the opening. Nozzle 15 is designed so that an internal scoop picks up material in chamber 10 and delivers it through the coupling 16 into the end of the continuous

spiral hose 2. The direction of flow of carbon granules is indicated by arrow B.

The mass of granules is conveyed in a continuously rolling manner but in separate volumes which occupy the lower segments of the spiral 5 hose, to the discharge chamber 17. Here the discharge end of the hose 2 is connected into the chamber 17 by a suitable nozzle 18 but without the internal scoop. The inner periphery of the chamber 17 is fitted with scoops 19 or any other 10 suitable device for lifting the granular material and delivering it into discharge line 20. The scoops 19 upon reaching the extreme upwardly position in their rotation, discharge the granules of carbon black which they have picked up in the 15 lower portion of the chamber into the spout 21. The spout 21 connects directly into the discharge line 20 and is also adjustable as indicated in Figure 2 of the drawings. By adjusting the spout 21, the amount of granules withdrawn from the 20 discharge chamber 17 can be regulated. Into line 20 is fed by line 22 a further increment of raw feed and line 20 enters the inlet chamber of a similar unit in series.

In operation of the apparatus line 8 conveys 25 granules of carbon black to the inlet end of the rubber hose 2 by means of the inlet chamber 10. The line 9 adds raw feed and also seed material if desired to the line 8. The drum 1 may be one of four operating in series and the line 8 may connect into another drum member 1. The drum 1 is rotated by the shaft 3 and seed and raw material in the inlet chamber 10 is scooped up from the bottom of the chamber by means of the 30 scoop 15 and enters the rubber hose 2. The amount of material in process is such that there will be no carry over in the rubber hose as the 35 hose is rotated, but the material will gently roll and advance along the Archimedes spiral. The inlet to the hose 2 from the chamber 10 should be a sweeping curve with no sharp bends therein as the material in process has a great tendency to clog and sharp bends are a factor to produce this clogging condition. The material 40 in process discharges into the chamber 17 at the other end of the drum by means of the nozzle outlet 18. The granules are picked up from the bottom of the chamber 17 by the scoops 19. The spout 21 which connects into the discharge 45 line 20 may be adjusted at any angle desirable for the output of product required. The scoops 19 always remain the same size and any excess of material delivered by the scoops 19 to the spout 21 will just fall to the bottom of the chamber 17. The amount of material removed from the chamber 17 is the same amount as enters the chamber 10. The discharge from chamber 17 enters line 20 which is joined by line 22 and line 50 20 enters another drum unit 1.

The reason for dividing the rotating mechanism into four or more similar units is primarily to permit the introduction of feed at several points in the cycle flow so that there will not be enough at any point to clog the rolling motion of the granules and so that there will be enough present throughout the Archimedes spiral to lubricate the granules against mutual attrition. A consequence of this division into units is that each becomes short enough to be built lightly and mounted on a shaft which is 55 more trouble free than the heavy metal cylinders mounted on trunnions of the prior art. The units may be arranged in a straight line with the discharge of the last, less the amount removed from the cycle for sifting as product, re- 60

turned to the inlet of the first by any suitable conveyor; or they may be arranged in two parallel lines, the cyclic material going out through one line and coming back to the inlet of the first unit by way of the second line.

The amount, and therefore the ratio, of cycle flow to feed may be governed by means of the gross amount of material contained in the spiral. The amount with which it is originally charged obviously governs the angular portion of each coil of the spiral that is filled and this may be increased or diminished by drawing off or adding to the cyclic material during operation.

Within the limits of clogging rotary motion of the granulator, or the other extreme, of failing to lubricate them against attrition, there is a control by means of the amount of feed introduced at various points. For example, no feed need be introduced at the last unit upstream from the point of drawing off product, thus giving the granules a final polish, free from feed, just before product is removed.

The control of flow velocity is by means of the speed of rotation of the rotating units and this flow velocity may be controlled independently of the cross section of the hose used or the gross amount of material contained in it. Seed for this cycle may be made by diverting a controlled portion through any adjustable device for breaking it, such controlled proportion to include first those granules sifted from the product as being oversize.

Figure 4 shows another design of apparatus which carries forward the same principles as previously described. The apparatus is exactly the same as Figure 1 in principle but instead of having a number of separate units in series, the disclosure in Figure 4 uses in one unit both a right hand 2" and left hand 2' spiral of rubber hose, the hose 2" being wrapped on the outside of the supporting shell 1' and the hose 2' being spirally coiled within and clamped to the inner surface of the supporting shell 1'.

The rotor or cylindrical drum or shell 1' is built of either wood or steel and is mounted to rotate on a horizontal shaft 3' by any suitable motor means. The shell 1' serves only as a support for the coiled hose 2' and 2" and need not be of rigid or heavy construction but possessed of enough strength to serve as a supporting means only. At each end of the shell or drum 1' and concentrically mounted on the shaft 3' are mounted the flat circular housing members 4' and 5' which are termed mixing and turning cells. The diameter of these cells (at right angle to the shaft) is less than the diameter of the cylindrical support by twice the overall diameter of the hose used. Each turning cell is provided with two radial nozzles 14' and 22'; 18' and 23' respectively, spaced 180 degrees apart. One nozzle on each end cell has a long sweep, namely nozzles 14' and 18', so that it may be flanged to the end of the hose 2" wrapped externally on the shell or drum 1. The other nozzles 22' and 23' on each end cell have a short sweep so they may be flanged to the ends of the hose 2' wrapped internally within the shell. On the end cell 4', both nozzles face right while those on the end cell 5' at the opposite end of the rotor both face left. The hose, both internal and external, is attached firmly to the supporting shell by clamps. The internal arrangement of the chambers 10' and 17' is shown in Figures 5 and 6, with the chamber 10' having the scoop 22" which 65 delivers material from chamber 10' to the inner

hose 2'. The hose 2' has the outlet 23' on the opposite end which delivers the material from the inner hose 2' to the chamber 17'. From chamber 17', scoop 18" delivers the material from chamber 17' to the external hose 2" and outlet 14' on the opposite end of the hose 2" delivers the material back to chamber 10'.

The whole arrangement amounts to a double spiral annulus which moves the granular material in a closed cycle from one mixing chamber to the other and back. The unit is fed at one or preferably both ends with raw feed and seed made in separate apparatus as clearly described in applicant's copending application, Serial No. 259,065 filed February 28, 1939. Clearly the greater the content of the apparatus, so long as material is not carried over the top in the hose, the more power is required to drive it. A recording ammeter shows the power required and therefore continuously indicates the weight of material in the closed cycle. There is removed at either end, even though it is being fed at both ends, product at such a rate as to hold the ammeter at constant load.

In this installation it is contemplated using 8 inch hose, two turns inside and 10 turns on the outside of a 10-foot diameter drum, making 500 feet of hose which will require that the drum be only 10 feet long and thus will give capacity for 14,000 pounds per day of feed.

The cell 5', the end at which the product is taken out, is provided with product lifting cups 19' located as shown in Figure 5 which will elevate material coming from the hose 2' discharging into chamber 17' and drop it into the product spout 21'. Though the lifting cups 19' dip and elevate a constant amount, by rotation of the product spout as shown in dotted line, more or less product is removed from the chamber 17' or the spout 21' may be so adjusted that no product is removed at all.

The double Archimedes spiral is set level, but it positively moves material in both directions at the same time, so that the material in process repeatedly passes points of feeding and of product removal. The small and large sizes, together with the feed and seed, are also repeatedly mixed in the end cells 4' and 5'. Besides being a practical way to use rubber as the surface material, to which carbon does not cling, there is about 20% more of this better rubber surface than in a metal annulus of the same cubic content.

The broad principles which have been set out in applicant's copending application, Serial No. 259,065, filed February 28, 1939, having to do with closed cycle, relative size of seed, maintenance in the cycle stream of granules larger than the product and geometrical limit to the size of these, apply equally to both disclosures which are also closed cycle processes.

It is to be understood that the form of my invention, herewith shown and described, is to be taken as a preferred example of the same, and that various changes in shape, size, and arrangement of parts, may be resorted to without departing from the spirit of my invention, or the scope of the subjoined claims.

Having thus described my invention, I claim:

1. Apparatus for agglomerating carbon black which comprises a rotatable supporting structure,

5 a conduit spirally wound on said rotatable supporting structure and rotatable therewith, a chamber on one end of the rotatable supporting structure from which the carbon black to be agglomerated is introduced to the spiral conduit, and a chamber at the other end of the rotatable supporting structure to receive the processed black from the spiral conduit, the carbon black itself in movement from one end to the other of the spiral conduit being the active mechanism which effects agglomeration.

2. Apparatus for agglomerating carbon black which comprises a rotatable supporting structure, a rubber hose spirally wound on said rotatable supporting structure and rotatable therewith, a chamber on one end of the rotatable supporting structure from which the carbon black to be agglomerated is introduced to the rubber hose and a chamber at the other end of the rotatable supporting structure to receive the processed black from the spiral rubber hose, the carbon black itself in movement from one end to the other of the spiral rubber hose being the active mechanism which effects agglomeration.

3. Apparatus for agglomerating carbon black which comprises a rotatable supporting structure, a conduit spirally wound on said rotatable supporting structure, a second conduit spirally wound in the opposite direction and externally of the first conduit and a chamber at each end of the supporting structure to receive processed carbon black from one conduit and to provide feed for the other conduit.

4. Apparatus for agglomerating carbon black which comprises a rotatable supporting structure, a rubber hose spirally wound on said rotatable supporting structure, a second rubber hose spirally wound in the opposite direction and externally of the first rubber hose and a chamber at each end of the supporting structure to receive processed carbon black from one of the rubber hoses and to provide feed for the other rubber hose.

5. Apparatus for agglomerating carbon black which comprises a rotatable supporting structure, a conduit spirally wound on said rotatable supporting structure, a second conduit spirally wound in the opposite direction and externally of the first conduit and a chamber at each end of the supporting structure to receive processed carbon black from one conduit and to provide feed for the other conduit, the carbon black itself in movement from one end to the other and back again in the spiral conduits being the active mechanism which effects agglomeration.

6. Apparatus for agglomerating carbon black which comprises a rotatable supporting structure, a rubber hose spirally wound on said rotatable supporting structure, a second rubber hose spirally wound in the opposite direction and externally of the first rubber hose and a chamber at each end of the supporting structure to receive the processed carbon black from one hose member and to provide feed for the other hose member, the carbon black itself in movement from one end to the other and back again in the spirally wound rubber hoses being the active mechanism which effects agglomeration.

SAMUEL C. CARNEY.

CERTIFICATE OF CORRECTION.

Patent No. 2,263,118.

November 18, 1941.

SAMUEL C. CARNEY.

It is hereby certified that error appears in the printed specification of the above numbered patent requiring correction as follows: Page 3, first column, line 26, for the word "two" read --ten--; and that the said Letters Patent should be read with this correction therein that the same may conform to the record of the case in the Patent Office.

Signed and sealed this 3rd day of March, A. D. 1942.

Henry Van Arsdale,

Acting Commissioner of Patents.
